Filed June 16, 1961, Ser. No. 117,730
8 Claims. (Cl. 338—174)

This invention relates to potentiometers, and more particularly, to thin rotary potentiometers having small external dimensions.

The recent increase in popularity of analogue networks for both computation and control of complex processes has increased the number of potentiometers being used. Although the potentiometer is ancient when compared with most electrical equipment, its use in new environments presents new problems in design and in construction. As the number of components which are connected together into a network increases, the need for reducing the size and weight of the individual units also increases. In addition, the recent demand for miniaturization has also supplied impetus to the design of smaller potentiometers. In some installations, many potentiometers are mounted to be driven by a single input device such as a servo motor. One manner in which this is accomplished is by the passage of a single drive shaft through all of a group of axially aligned potentiometers whereby, the space required for individual drives is eliminated and the space between potentiometers usually occupied by driving means from one to the other is saved. Further, the reduction in the size of the potentiometers themselves has resulted in savings in space and materials.

However, as the size of the potentiometers has decreased, new problems have been created. The reduction in size of the outside diameters of the potentiometers also means a reduction in the size of the internal elements, or a rearrangement of the parts to provide the accuracy required. In addition, in precision potentiometers such as those used in telemetering, the arrangement of the internal elements must be such as to achieve the desired rotation-resistance characteristics. With the decrease in the size of the internal mechanism, the desired accuracy becomes more difficult to achieve.

It is an object of this invention to provide a new and improved small potentiometer.

Another object of this invention is to provide a new and improved electrical contacting arrangement which introduces very little noise into the potentiometer output.

A further object of this invention is to provide an improved internal arrangement for a potentiometer take-off, having a greater degree of reliability than prior take-offs.

Other objects and advantages of this invention will become apparent as the following description proceeds, which description should be considered together with the accompanying drawings in which:

FIG. 1 is a sectional view of a potentiometer arranged to be coaxially mounted with other such potentiometers;

FIG. 2 is a sectional view of a portion of the potentiometer of FIG. 1;

FIG. 3 is a sectional view of the eyelet and washer assembly of the potentiometers of FIGS. 1 and 2;

FIG. 4 is a rear view of the assembly of FIG. 2;

FIG. 5 is a sectional view of a potentiometer arranged to be separately mounted and incorporating the principles of this invention; and

FIG. 6 is a plan view of the brush spring and contact member used in the potentiometers of FIGS. 1 and 5.

Referring now to the drawings in detail, the reference character 11 designates a potentiometer housing made of any suitable construction material, such as stainless steel,

2

aluminum, synthetic resin, and the like. A clamping ring 12 connects the housing 11 with the housing 13 of an adjacent potentiometer. Within the housing 11, a support member 14 of electrical insulating material carries a resistance element 15 formed of conductive plastic, wire, or a high resistance coating on an insulating base. A sliding brush member 16A is carried by spring member 16 which has the general shape of the combined brush and spring member shown in FIG. 6. The spring member 10 may be made of beryllium copper or other suitable spring material. Spring member 16 is carried by shaft 17. Brush member 16A bears against the top surface of the resistance element 15 to make a sliding electrical connection therewith. Bearings 18 support the shaft 17 in an end wall of the housing 11 and at other points, not shown, for free rotation. A moving brush block 19 comprising metallic portion 19A and insulator portion 19B suitably bound together is mechanically connected to the shaft 17 for rotation therewith by means of a set screw 21 or other suitable means. The shaft 17 passes through an eyelet 23 which supports a washer-like, precious metal contact 24 and serves to attach terminal board 27 to support member 14. The terminal board also serves as a means for connecting internal terminals 26 and eyelet 23 with external terminals 28 by means of circuitry printed on the terminal board and shown in FIG. 4. An insulator washer 25 made of a dielectric material such as Mylar is confined between flange 35 and a raised portion of support piece 14 and prevents short circuiting the internal terminals 26, and eyelet 23. Terminals 26 are electrically connected by conductive parts 33 to the ends of resistive element 15.

It is noteworthy that the above described arrangement of parts 23 and 24 separated from terminals 26 by insulator 25 permits these parts to overlie one another in close proximity. The alternative would be to have the washer 24 or its equivalent and terminals 26 arranged in concentric circles on support member 14. This conventional alternative would objectionably increase the diameter of the total assembly. The arrangement of FIG. 1 permits the design of precision potentiometers, having overall casing diameters as small as $\frac{1}{2}$ inch. These advantages are particularly important in the design of miniature conductive plastic potentiometers as illustrated.

The manner in which the resistance element, terminal board, and support member are connected is better seen in FIG. 2. The eyelet 23, as shown in FIG. 3, comprises a central barrel portion 34, two tabs 31 at one end of the barrel 34, and a flange 35 at the other end of the barrel 34. The resistance element 15 is molded, or otherwise fastened, to the support block 14 so as to form a concentric circular track about a central perforation in the support block 14. The terminal board 27 also has a perforation, and the barrel portion 34 is inserted through the aligned perforations in the board 27 and the support member 14. When the tabs 31 are bent outwardly against the back of the terminal board 27, the assembly is gripped between the flange 35 and the tabs 31, and an electrical connection is established between some of the circuitry 38 on the back of the panel board 27 and the flange 35. The washer 24 is fastened to the outside of the flange 35 by any suitable means, such as by soldering or brazing, and, in the completed assembly, is contacted by a portion of sliding brush members 20 carried on either inner arm of spring member 16 shaped as in FIG. 6. In this manner, an electrical circuit is formed from an intermediate point on the resistance element 15, through the brush contact 16 and the brush spring to the brush contacts 20, the washer 24, flange 35, barrel 34, tabs 31 to the circuitry on the terminal board 27 and an external terminal 28. Terminals 26, which also act as rivets,

further serve to fasten the board 27 to the support block 14 and connect the ends of the resistance track 15 to circuitry 38 on the back of the board 27.

In the assembly of FIG. 1 insulator member 40 surrounds the shaft from the brush block of one cup to the brush block of the next. It serves to prevent "hi-pot" or short circuiting between shaft and active potentiometer elements such as spring 16 and washer 24. Cover piece 41 serves to protect and support board 27 carrying printed circuit member 38. Cover 41 and the entire element assembly are urged in the direction of the brush block by spring 42 so that support piece 14 bears on shoulder 43 in case 11. Case 11 has a milled slot at one side extending from the end of the case to the assembled position of the terminal board 27 and of width to fit the last mentioned part. The element assembly as shown in FIG. 2 is inserted into case 11 with shaft 17 and brush block 19 with all attached parts preassembled. Cover piece 41, spring 42 and succeeding case 13 are then assembled. The slot behind terminal board 27 is then filled with closure piece 44 which is held in place between clamp 12 and case 13.

An alternative construction for bringing connections to the side of a ganged potentiometer is to remove printed circuit board 27 entirely and to attach wires to terminals 26 and tabs 31 and bring these wires out as a cable through the opening in the potentiometer casing otherwise occupied by the printed circuit board. The remaining space otherwise occupied by the printed circuit board is filled with suitable potting compound.

Washer 24 and brush member 16 are preferably formed of a noble metal, such as a platinum-palladium alloy, and contact 20 is preferably formed of a gold alloy to maintain contact resistance and noise levels low.

When a potentiometer is constructed for use as a single resistive element, terminals are usually provided at its back. Such a potentiometer is illustrated in section in FIG. 5 and comprises a housing 51 having a bearing 52 at one end for rotatably supporting a shaft 53, and an end plug 54 of electrically insulating material. A thrust bearing 55 carried by the end plug 54 rotatably supports the other end of shaft 53. An insulator brush-block 56 is attached to the shaft 53 in a suitable manner such as by molding thereon, to rotate therewith. Fastened to the brush block 56, such as by a rivet 57, is a resilient brush member 58, such as that shown in FIG. 6. The brush member 58 comprises a first curved portion 61 and a second curved portion 62 having a radius much smaller than that of the first portion 61.

A resistance track 59, similar to the resistance track 15 of FIGS. 1 and 2, is supported on the end plug 54 and may be an integral part thereof. A downwardly curved or hooked portion near the end of the first curved portion 61 of the brush 58 slidably engages the top of the resistance track 59 to make electrical contact therewith, and dimples near the ends of the second curved portion 62 of the brush 58 slidably engage a washer-like slip-ring 63 formed of a low resistance precious metal alloy such as a gold alloy. A first external terminal 65 extends through the end plug 54 and is electrically connected to the washer 63. External terminals 66 (only one of which is shown) also penetrate the end plug 54 and make electrical connection with the ends of the track 59 by means of conductive pieces 67. A washer 64 of insulating material insulates the under-side of the washer contact 63 from the ends of the terminals 66. Terminal 65 and similar dummy members not shown and not reaching the outside of the potentiometer also serve as rivets to fasten together the end plug 54 and the washers 63 and 64.

The brush member 58 is better illustrated in FIG. 6 which clearly shows the first portion 61 having a larger radius than the second portion 62. The ends of both portions are bent downwardly at an angle to the rest of the brush member 58 so that the ends bear against the resistance track 59 and the washer 63. The brush mem-

ber 58 is fastened to the brush block by rivets 57 passing through the holes 68 and 69. Member 58 is made of a precious metal having spring properties such as a platinum-palladium alloy. Dimples and curved portions are provided for point contact with the flat surface of washer 64 and the curved surface of element 59.

As used in the assembly of FIGURE 1, flat beryllium copper spring 16 has the general shape of spring 58. Downwardly bent portion of 61 is replaced for instance by a half-round piece of precious metal 16A in the same position and the dimples in 62 are replaced by buttons of precious metal which may be molded or soldered to the spring.

In the structure of both FIGS. 1 and 5, the electrical circuitry inside the casing is completed by using a washer-like slip-ring made of a precious metal alloy to provide an electrical connection between one portion of the brush member and the external terminals. There exist, therefore, in each potentiometer casing, two tracks slidably contacted by the ends of the brush member, one track being a resistive element and the other track having a low resistance. The inner, low resistance track overlies the terminal members attached to the outer resistive element. In this manner, the size of the potentiometer may be quite small without impairing the operability of the device. Since the two tracks are essentially concentric, space which is ordinarily wasted in the potentiometer is utilized to maintain accuracy in a smaller casing.

This specification has described a new and improved 30 potentiometer for use in precision equipment where small size and weight are important. The structure described comprises a resistive track and a conductive track essentially coaxial with each other within the potentiometer casing, and brush means slidably contacting both to establish internal electrical connections which can be extended outside of the casing. It is realized that the above description will indicate to those skilled in the art other ways in which the invention may be used, and it is, therefore, intended that this invention be limited only by the scope of the appended claims.

What is claimed is:

1. A potentiometer comprising a casing, a shaft passing through at least one end of said casing, a brush member having a first brush portion and a second brush portion mounted on said shaft and electrically connected to one another, a resistance element mounted on an insulator base within said casing substantially concentric with said shaft, internal terminal means for said resistance element mounted on said base and closer to said shaft than said resistance element, said resistance element being positioned so that it is slidably engaged by said first brush portion, a slip-ring of high conductance mounted within said casing substantially concentric with said resistance element and positioned to be slidably engaged by said second brush portion, said slip-ring overlying said internal terminal means in an axial direction with respect to said shaft the outer diameter of said slip-ring being greater than the distance of said internal terminals from said shaft and less than the internal diameter of said resistance element, and means for connecting external terminals to said internal terminal means and said slip-ring.

2. The potentiometer defined in claim 1 wherein an insulator member is interposed between said slip-ring and said internal terminal means.

3. A potentiometer comprising a housing having aligned perforations through its end walls, a shaft passing through said perforations, a resistance element generally concentric with said shaft, terminals for said resistance element lying closer to said shaft than said element, a first brush portion mounted on said shaft to be positioned thereby and adapted to contact said resistance element, a second brush portion, mounted on said shaft and electrically connected to said first brush por-

tion, and a slip-ring generally concentric with said shaft and adapted to be connected to external circuitry for said second brush portion, said slip ring overlying said terminals in an axial direction with respect to said shaft the outer diameter of said slip-ring being greater than the distance of said internal terminals from said shaft and less than the internal diameter of said resistance element.

4. The potentiometer defined in claim 3 wherein an insulator member is interposed between said slip ring and said internal terminals.

5. A potentiometer comprising a generally cylindrical housing having ends, said ends having generally central perforations, a shaft mounted for rotation in said housing and passing through said perforations, a resistance element generally concentric with said shaft, terminals for said resistance element lying between said element and said shaft, a brush assembly mounted on said shaft for rotation therewith, said brush assembly including a first brush portion contacting a surface of said resistance element, a terminal board for connecting said potentiometer to external circuitry, a member for mechanically coupling said terminal board and said resistance element, a slip-ring mounted on said member and electrically connected to said terminal board, and a second brush portion in said

brush assembly adapted to contact said slip-ring, said slip-ring overlying said terminals in an axial direction with respect to said shaft the outer diameter of said slip-ring being greater than the distance of said internal terminals from said shaft and less than the internal diameter of said resistance element.

6. The potentiometer defined in claim 5 wherein an insulator member is interposed between said slip-ring and said internal terminals.

10 7. The potentiometer defined in claim 5 wherein said mechanically connecting means comprises a generally cylindrical barrel portion having a flange at one end and tabs at the other end, said slip-ring being mounted on said flange.

15 8. The potentiometer defined in claim 7 wherein an insulator member is interposed between said slip-ring and said internal terminals.
